UNITED STATES PATENT OFFICE.

SVEN T. NELSON, OF CHICAGO, ILLINOIS, ASSIGNOR TO SULLIVAN MACHINERY COMPANY, OF CHICAGO, ILLINOIS, A CORPORATION.

HOISTING-ENGINE.

No. 900,768.

Specification of Letters Patent.

Patented Oct. 13, 1908.

Application filed May 9, 1906. Serial No. 315,955.

To all whom it may concern:

Be it known that I, SVEN T. NELSON, a citizen of the United States, and a resident of Chicago, county of Cook, and State of Illinois, have invented certain new and useful Improvements in Hoisting-Engines, of which the following is declared to be a full, clear, and exact description.

The invention relates to hoisting engines for operating the cages or "skips" in mines and the improvement seeks to provide a safety mechanism for automatically cutting off or throttling the supply of motor fluid to the engine before the cage reaches the end of its upward travel in the mine shaft.

A further object of the invention is to provide means whereby the operation of the engine reverse gear and the clutch mechanism for coupling the hoisting drums to the engine shaft, will release or restore the automatic throttling mechanism.

With these and other objects in view the invention consists in the features of construction, combinations and arrangements of parts hereinafter set forth, illustrated in the accompanying drawings and more particularly pointed out in the appended claims.

The invention is more particularly applicable to a double drum hoist, in which two drums are mounted on the engine shaft, the cables being wound thereon in opposite directions so that the two cars or cages may be hoisted "in balance" if desired. Suitable clutch mechanism, as usual, is provided for connecting either or both drums to the engine shaft and suitable reverse gear is provided for the engine. Means are provided in connection with each drum for automatically throttling the engine at a predetermined point or when the car approaches the upper end of the mine shaft. The clutch and reverse operating gear is connected to disengage the automatic throttling mechanism so as to permit the further operation of the engine. As usual with such double drum hoists, both drums are mounted upon a common engine shaft and there are two engines, one coupled to each end of the shaft.

In the drawings, Figure 1 is a partial plan view of the double drum hoist with the improved controlling mechanisms applied thereto. Fig. 2 is an elevation of one of the engines with parts shown in section on the line 2—2 of Fig. 1. Fig. 3 is a view in elevation of the automatic throttling mechanism

with parts shown in section on the lines 3—3 of Figs. 1 and 4. Fig. 4 is a plan view of the automatic throttling mechanism. Fig. 5 is a detail view in elevation of a portion of the automatic throttling mechanism with parts shown in section on the line 5—5 of Fig. 4. Fig. 6 is a detail section on the line 6—6 of Fig. 4. Fig. 7 is a view in elevation of the reverse and clutch operating mechanisms with parts broken away and parts in section on the line 7—7 of Fig. 1. Fig. 8 is a detail view of the reverse mechanism with parts shown in section on the line 8—8 of Fig. 1. Fig. 9 is an elevation of the clutch mechanism with parts in section on line 9—9 of Fig. 1.

In the form shown, the drums A, A' are mounted upon a common engine shaft *a*. As stated, the cables for the two cars or cages are wound in opposite directions about the drums so that they will be hoisted "in balance" when both drums are coupled to the shaft; that is to say, one car will be raised as the other is lowered. The engine shaft is journaled in a suitable central bearing 10 and at its ends in bearings 11 at the forward end of the engine frame 12. As stated, there is an engine at each end of the shaft *a*, only one of which is shown. It will be understood that the other engine is of similar construction. The shaft *a* is provided at each end with a crank 13 coupled by a connecting rod 14 to the adjacent engine. The engine cylinders 15, as shown, are provided (see Figs. 1 and 2) with the ordinary Corliss valve gear driven from a wrist-plate 16. The latter are driven by connecting rods 17 coupled at their forward ends to crank pins 18 on the ends of the valve shaft *b*. This shaft extends from side to side in front of the drums A, A' and is journaled at either end in suitable bearings 19 on the engine frames 12 and in intermediate bearings 20, 21 and 22 arranged on suitable standards rising from the foundation of the engine.

At one end (see Figs. 1, 7 and 8) valve shaft *b* is provided with a gear 23 that is driven from the gear 24 on the engine shaft *a* through the medium of an intermediate idler 25. Gear 23 is loose on the shaft but is provided with a pair of stops or lugs 26 (see Fig. 8) arranged to engage an arm 27 that is fixed to the shaft so that the valve shaft may be properly driven in one or the other direction. By shifting the valve shaft *b* to move

the arm 27 away from one of the stops or lugs 26 into engagement with the other stop or lug the valve gear is properly positioned to reverse the engine. Any suitable means 5 may be provided for shifting the valve shaft. In the form shown, gear 23 is connected to the end of a sleeve 28 loosely mounted on the shaft. At its opposite end the sleeve 28 is provided with a half-portion 29 of a quick 10 threaded screw. The other half portion 30 of the screw is fixed to the valve shaft *b*. A split nut 31 engages the screw sections 29 and 30 and by shifting the nut the valve shaft *b* may be rotated to reverse the 15 engine.

A small auxiliary engine *B* is preferably provided for shifting the reversing nut 31. This engine is mounted in a suitable frame 32 fixed upon a bed plate 33 and supporting 20 at its upper end the bearing 22 for the valve shaft. A split ring 34 arranged between a pair of flanges 35 on the nut 31 is provided with pintles 36 engaging the upper ends of a pair of arms 37. These arms are pivoted 25 intermediate their ends to the engine frame by a cross bolt 38. The lower ends of the arms are connected by links 39 to a cross head 40 on the piston rod 41 of the reversing engine *B*. The valve stem 42 of the reverse engine 30 is provided with a crank arm 43 that is connected by a link 44 to a rocker arm 45. The rocker arm 45 is connected by a link 46 to an arm 47 (see Fig. 1) on a rock shaft 48. This rock shaft is journaled at its forward end in a 35 bearing 49 and extends rearwardly beneath the engineer's platform *C*. As shown in Fig. 4, shaft 48 is journaled in a bearing 50 on one side of a supporting standard 51 for the platform *C*. A crank arm 52 on the rear 40 end of the shaft is connected by a link 53 to a hand lever 54 on the engineer's platform. By the connections described the valve of the reverse engine may be shifted by the 45 engineer to change the direction of the movement of the engine shaft.

Each of the drums is arranged to be coupled to the engine shaft *a* by a suitable clutch mechanism shown in detail in Figs. 7 and 9. A clutch band *D* is arranged to engage a projecting flange *d* on the outer end of the drum. One end of the band is secured to a projecting lug 55 that is rigidly mounted upon a head *E* keyed to the shaft. The opposite end of the clutch band is connected to the projecting end of a shift lever *e* that is pivotally mounted on a stud shaft 56 carried at the outer portion of the clutch head or member *E*. A grooved collar 57 is mounted to slide upon the hub of the clutch head or member *E* and to rotate therewith. A toggle link 58 pivoted between a pair of lugs 59 on the collar 57, is connected to the inner end of the band operating lever *e*. By shifting the collar 57 longitudinally upon the 65 hub of the clutch member *E*, clutch band *d*

can be shifted into and out of frictional engagement with the ledge or shoulder *d* on the drum *A*.

A split ring 60 engaging the grooved collar 57 is pivotally connected to the upper ends of a pair of arms 61 upon a rock shaft 62. This shaft is journaled at its forward end in a bracket 63 fixed to the adjacent engine frame and at its rear end in an upright 64 rising from the foundation of the engine. 75 Upright auxiliary engines *F* are preferably provided for operating the clutches. An arm 65 on the end of the rock shaft 62 extends through a slotted cross head 66 on the piston rod 67 of the clutch engine. The end 80 of the arm 65 is slotted and a block 68 within the slot is mounted upon a cross pin 69 that is fixed to the cross head 66. The valve stem *f* of the clutch engine *F* is provided with a rock arm 70 connected by a link 81 to a rock arm 82 on the short shaft 83 journaled in a bracket 84. A rock arm 85 on the opposite end of the shaft is connected by a link 86 (see Figs. 1 and 2) to a crank arm 87 on a cross shaft 88 that is journaled in suitable 90 bearings 89 on the bed plate 33 beneath the engineer's platform. There are two of these shafts one for each clutch engine and each shaft is provided at its inner end with a rock arm 90 connected by a link 91 to a shift lever 95 (see Fig. 1) on the engineer's platform *C*. By shifting the hand levers 92 the clutch engines *F* may be operated to couple and uncouple the drums *A* *A'* on the engine shaft.

A throttle operating shaft *g* extends transversely between the engines and is journaled at its ends (see Figs. 1 and 2) in brackets 93. Intermediate its ends this shaft is journaled in bearings 94 upon the bed plate 33. At each end (see Fig. 2) shaft *g* is provided with 100 a crank arm 95 connected by a link 97 to an arm 98 on a short shaft 99 journaled on the upper portion of the adjacent engine frame 12. Shaft 99 is provided with an arm 100 connected by a link 101 to one arm of a bell 110 crank 102, the other arm of which is connected to a stem 103 of the throttle valve *G* on the engine cylinder. Bell crank 102 is carried upon a pair of swinging links 104 (see Figs. 1 and 2) that are pivotally mounted on the casing of the throttle valve. Throttle shaft *g* is provided adjacent the brackets 94 (see Figs. 1, 3 and 4) with two crank arms 105 connected by links 106 to crank arms 107 keyed to a shaft 108 journaled in suitable bearings on the under side of the engineer's platform *C*. A hand lever 109 (see Figs. 1 and 3) is also keyed to the shaft 108. The other hand levers 54 and 92 are loosely mounted on the shaft 108. By 125 shifting the hand lever 109 the engineer may open and close the throttle valves of both engines.

Suitable mechanism is provided that is controlled by the movement of the drums 130

A A' for automatically closing the throttles. For this purpose, (see Figs. 1, 3, 4 and 5) the throttle shaft *g* is provided with a pair of shifters in the form of arms *H* that are keyed 5 to the shaft to rotate therewith, but are movable longitudinally thereon. These shifter arms are connected by bolts 110 to split collars 111 on the opposite ends of a sleeve *h* mounted on the throttle shaft *g*. Each split 10 collar 111 is mounted to slide upon the reduced end of the sleeve *h* but is normally held against a flange 112 on the end of the sleeve by a spring 113 extending between the collar and a shoulder 114 on the sleeve. The 15 springs 113 yieldingly hold the shifter arms in their outermost position. The throttle shaft *g* and the sleeve *h* thereon are arranged just beneath the reverse controlling shaft 48. Sleeve *h* is longitudinally shiftable on the 20 throttle shaft *g* and is provided on its upper face with a short rack *L* which meshes with a spur gear *l* on the reverse controlling shaft. The gear *l* is arranged adjacent a bracket *l'* in which the reverse shaft 48 is journaled at 25 this point. It is obvious that by this arrangement sleeve *h* and shifters *H* are moved back and forth upon the throttle shaft as the engine is reversed.

Suitable actuators are provided for the 30 shifters *H* in the form of disk cams *J*. These actuating cam members are mounted on suitable uprights or standards 115 beneath the engineer's platform. In the upper end of each standard (see Fig. 6) is journaled a 35 sleeve 116 which is held against longitudinal movement through the standard by a worm wheel 117 on one end and a collar 118 on its opposite end. Through each sleeve extends a hollow shaft *j* upon the outer ends of which 40 the actuating cam members *J* are keyed. The hollow shaft *j* is keyed to the sleeve 116 to rotate therewith, but is longitudinally movable through the sleeve. This longitudinal movement of the hollow shaft *j* and actuating cam member *J* is effected by a screw 45 *K* threaded into the inner end of the hollow shaft and rigidly mounted upon a bracket *k* secured to the standard 115. A pair of actuating shafts *M* are journaled at their rear 50 ends in the standards 115 and at their forward ends in suitable brackets 119 (see Fig. 1). The forward ends of these shafts are connected by beveled gears 120 to short stud shafts 121 journaled in brackets 122. Spur 55 gears 123 on shafts 121 are driven from gears 124 through the medium of intermediate idlers 125. The two spur gears are connected to the inner ends of the respective drums A A' so that the shafts *M* are driven in 60 correspondence with the movements of the drums. At their rear ends the shafts *M* are provided with worms *m* engaging the worm wheels 117. By the gearing described, the 65 operation of either drum will rotate the corresponding cam member *J* and will also

slowly reciprocate it back and forth in accordance with the direction in which the drum is moving. The screws *K* for reciprocating the cam disks *J* are right and left screws so that when both drums are coupled 70 to the engine shaft and the operating shafts *M* rotated in opposite directions, the cam disks *J* themselves will be moved longitudinally in the same direction, but will be rotated in opposite directions. 75

Each cam disk *J* is provided on its periphery with a flanged portion 126 having inclined cam teeth or ledges 127 cut on its inner face. These cam ledges are arranged to cooperate with rollers 128 mounted in inclined 80 position upon the shifter arms *H*.

As above noted, the cables are wound on the drums in opposite directions so that when both are connected to the engine shaft one of the cages is raised while the other is 85 lowered. The arrangement of the reverse gear is such that when either drum is rotated in proper direction to raise its corresponding cage, the sleeve *h* will be in position to hold the shifter *H* at one end toward the cam member *J* corresponding to the drum that is lifting its cage. The shifter *H* at the other end of the sleeve will be held away from its actuating cam member *J* and out of operative 90 relation therewith. The gearing between 95 the drums A A' and the actuating cam members *J* is such that as either cage is raised the corresponding cam member will move inwardly towards the adjacent shifter *H* and at a predetermined point the cam ledges or 100 teeth 127 thereon will engage the roller 128 of the shifter *H* to rotate the throttle shaft *g* and close the throttles.

The automatic throttling mechanism is set 105 to close the throttle valves when either car is within two or three hundred feet of the upper end of the mine shaft, so that the lift of the car is completed by the momentum of the moving parts and so that the brake mechanism (of which any suitable form may 110 be used) can be subsequently applied to promptly stop the engine and the cages or cars operated thereby. It is difficult and sometimes impossible to arrest the movement of the engine by the brake when the engine is running under a full head of steam, so 115 that ordinarily the engineer must first close the throttles before operating the brake. In the present construction, the safety mechanism automatically closes the throttles so that 120 the brakes may thereafter be readily applied, either by hand or automatically to prevent accident. In prior constructions automatic brakes have been used but if the engineer were careless or negligent the automatic 125 brake mechanism must stop the engine while moving under a full head of steam, whereas in the present construction the throttling valves are first automatically closed and thereafter any suitable form of automatic 130

brake mechanism may be used to arrest the movement of the engines.

When either of the shifters H have been operated by the corresponding actuator J to close the throttles, the engineer may reverse the engine and in so doing shift the sleeve h to disengage the shifter H from its actuating cam member J. The engineer can then open the throttles to run the engine in reverse direction. Means are also provided for disengaging or restoring the automatic throttle mechanism when the latter is operated by either drum to close the throttles, by disengaging the clutch mechanism of that drum. For this purpose, each of the clutch controlling shafts 88 is provided with a crank arm 129 that is connected by a link 130 to a rock arm 131 on a short vertical shaft 132 journaled in a bracket 133. A pair of arms 134 on the shaft 132 are arranged to project on opposite sides of the throttle shaft G in proper position to engage the adjacent shifter arm H. The arrangement is such that while either of the clutch levers 92 are moved to disconnect one or the other of the drums, the corresponding shifter H will be moved by the arms 134 against the tension of spring 113 to a position out of the path of movement of its actuating cam member J. It will thus be seen that when either drum is coupled to the engine shaft and the engine shaft is rotating in proper direction to raise the cage connected to that drum, the automatic throttle mechanism will be in proper position to shut off the supply of motor fluid to the engines when the cage has reached a predetermined point adjacent the top of the mine shaft. By reversing the engine to lower the cage or by disconnecting its drum from the engine shaft, the engineer may throw the parts of the throttling mechanism out of coöperative relation so that he may then open the throttles. He is however compelled to do either one or the other and cannot through carelessness or negligence run either car under a full head of steam up to the top of the mine shaft. The flange 126 on the cam member J is provided with a series of cam ledges or teeth so that it will properly engage the roller 128 on the shifter H, even though the cam member be moved into line with the roller when the flange 126 is opposite the same.

It is obvious that numerous changes may be made in the details of structure and arrangement of parts without departure from the essentials of the invention.

Having described my invention, what I claim as new and desire to secure by Letters Patent is:—

1. In a hoisting engine, the combination with the engine shaft, hoisting drum and clutch mechanism for connecting said drum to said shaft, of mechanism for automatically throttling the flow of motor fluid to the engine at a predetermined point and means

controlled by the operation of said clutch mechanism for restoring said throttling mechanism.

2. In a hoisting engine, the combination with a plurality of hoisting drums, a common engine shaft, and separate clutch mechanisms for connecting and disconnecting each of said drums and said shaft, of mechanism for cutting off the flow of motor fluid to said engine, and means driven by each of said drums for actuating said mechanism at a predetermined point.

3. In a hoisting engine, the combination with the engine shaft, hoisting drum and clutch mechanism for coupling said drum to said shaft, of throttling mechanism for the engine, means actuated by the drum for operating said throttling mechanism at a predetermined point and means controlled by the operation of said clutch mechanism for disengaging said operating means.

4. In a hoisting engine, the combination with the engine shaft, hoisting drum and clutch mechanism for coupling said drum to said shaft, of throttling mechanism for the engine, actuating means driven by the drum for automatically operating said throttling mechanism at a predetermined point and a clutch controlling gear arranged to restore said automatic operating means.

5. In a hoisting engine, the combination with a plurality of hoisting drums, a common engine shaft, and separate clutch mechanisms for connecting and disconnecting each of said drums and said common shaft, of throttling mechanism for the engine and separate actuating devices, one geared to and driven by each of said drums, for operating said throttling mechanism at predetermined points.

6. In a hoisting engine, the combination with the engine shaft, hoisting drum and clutch mechanism for coupling said drum to the engine shaft, of throttling mechanism for the engine, a shifter for said throttling mechanism, an actuator continuously driven from the drum for operating said shifter at a predetermined point and means controlled by said clutch mechanism for disengaging said actuator and said shifter.

7. In a hoisting engine, the combination with the engine shaft, hoisting drum and clutch mechanism for coupling said drum to the engine shaft, of throttling mechanism for the engine, an operating shifter for said throttling mechanism, an actuator continuously driven from the drum for operating said shifter at a predetermined point and a clutch controlling gear having means for disengaging said shifter from said actuator.

8. In a hoisting engine, the combination with a pair of hoisting drums, a common engine shaft, and separate clutch mechanisms for connecting and disconnecting each of said drums and said common shaft, a throttle

valve for the engine, a rock shaft connected with the throttle valve, shifter arms on said rock shaft and actuating cam members for said shifter arms, one of said cam members being driven by each of said drums.

9. In a hoisting engine, the combination with the engine shaft, hoisting drum and clutch mechanism for coupling said drum to said shaft, a throttle valve for the engine, a

10 rock shaft connected with the throttle valve, a shifter arm keyed on said shaft, longitudinally movable thereon and spring-held in normal position, an actuating cam member driven from the said drum arranged to en-

15 gage and operate said arm and rock shaft at a predetermined point and clutch controlling gear having means for moving said shifter arm out of engagement with said actuating cam member.

20 10. In a hoisting engine, the combination with the engine shaft, hoisting drum and clutch mechanism for coupling said drum to said shaft, a throttle valve for the engine, a rock shaft connected with the throttle valve,

25 a shifter arm on said rock shaft, an actuating cam disk and means driven from said drum for rotating said disk and shifting the same laterally to engage and operate said shifter arm at a predetermined point.

30 11. In a hoisting engine, the combination with the engine shaft, hoisting drum and clutch mechanism for coupling said drum to said shaft, a throttle valve for the engine, a rock shaft connected with the throttle valve,

35 a shifter arm keyed on said rock shaft and spring-held to yield longitudinally thereon, a rotary actuating cam disk and means driven from said drum for rotating said disk and moving the same toward said shifter arm to

40 engage and operate the same at a predetermined point, said cam disk having a projecting flange with a series of cam ledges or teeth thereon and said shifter arm having an inclined roller on its end for engagement with

45 said cam teeth or ledges.

12. In a hoisting engine, the combination with a pair of hoisting drums, a common engine shaft, and separate clutch mechanisms

50 for connecting and disconnecting each of said drums and said common shaft, of devices operated by each of said drums for throttling the flow of motor fluid to the engine at predetermined points, and means controlled by the operation of each clutch mechanism for

55 restoring the corresponding throttling devices.

13. In a hoisting engine, the combination with the engine shaft, a pair of hoisting drums and clutch mechanism for connecting said drums to the engine shaft, of throttling

60 mechanism for the engine and actuator mechanism driven by each of said drums for operating said throttling mechanism at predetermined points and means for operating the clutch of each drum connected to disengage

65 the corresponding actuating mechanism.

14. In a hoisting engine, the combination with an engine shaft, two drums mounted thereon and separate clutch mechanisms for coupling said drums to said shaft, of throttling mechanism for the engine, operating 70 shifters for said throttling mechanism, actuators driven from said drums for engaging and operating said shifters at predetermined points and means controlled by the operation of either clutch mechanism for throwing the 75 corresponding shifter and actuator out of operative relation.

15. In a hoisting engine, the combination with the engine shaft, hoisting drum thereon and clutch for coupling said drum to said 80 shaft, of throttling mechanism for the hoisting engine, actuating means driven from the drum for operating said throttling mechanism at a predetermined point, an auxiliary engine for operating said clutch and controlling 85 valve gear for said clutch engine having means for throwing said throttle actuating means out of operative position.

16. In a hoisting engine, the combination with the engine shaft and hoisting drum 90 thereon, of a throttle valve for the engine, an operating rock shaft connected to said throttle valve, a shifter arm on said rock shaft, an actuating cam member driven from said drum for engaging and operating said shifter 95 arm at a predetermined point and reverse gear for the hoisting engine connected to disengage said shifter arm and said actuator.

17. In a hoisting engine, the combination with the engine shaft and hoisting drum 100 thereon, of a throttle valve for the engine, an operating rock shaft connected to said throttle valve, a shifter arm keyed on said rock shaft and longitudinally shiftable thereon, an actuating cam member driven from the drum 105 for engaging and operating said shifter arm at a predetermined point, reverse gear for the hoisting engine, an auxiliary engine for operating said reverse gear and valve controlling mechanism for said reverse engine connected 110 to move said shifter arm longitudinally out of operative relation with said actuating cam member.

18. In a hoisting engine, the combination with the engine shaft, a pair of hoisting 115 drums, clutch mechanisms for coupling said drums to said shaft, of throttling mechanism for said engine, separate actuating mechanisms, one driven from each of said drums, for operating said throttling mechanism at predetermined points and reverse gear for said engine connected to throw one of said actuating mechanisms out of operation and the other into operative position.

19. In a hoisting engine, the combination 125 with the engine shaft, a pair of drums mounted thereon and clutch mechanisms for coupling said drums to said shaft, of throttling mechanism for the engine, a pair of shifters therefor, a pair of actuating members, one 130

driven from each of said drums, arranged to engage and operate said shifters at predetermined points and engine reverse gear connected to move one of said actuators and its 5 shifter out of operative relation and the other actuator and shifter into operative relation.

20. In a hoisting engine, the combination with the engine shaft, a pair of drums on said shaft and clutch mechanisms for coupling 10 said drums to said shaft, of throttling valves for the engine, an operating rock shaft therefor, a pair of shifters keyed and longitudinally shiftable on said rock shaft, a pair of actuating cam members, one driven from 15 each of said drums arranged to engage and operate said shifters at predetermined points and engine reverse gear connected to said shifters to move one shifter out of and the other into operative relation with its actuators. 20

21. In a hoisting engine, the combination with the engine shaft, a pair of drums on said shaft, clutch mechanisms for connecting said drums to said shaft, of throttle valves for the 25 engine, an operating rock shaft connected to said valves, a pair of shifter arms on said rock shaft, a longitudinally shiftable sleeve on said shaft to which said arms are connected, a pair of actuating cam members, one 30 driven from each of said drums for engaging and operating said shifter arms at predetermined points, engine reverse gear, an auxiliary engine for said reverse gear and valve gear for said reverse engine connected to 35 move said sleeve to throw one of said shifter arms into and the other out of operative relation with its actuator.

22. In a hoisting engine, the combination with the engine shaft, a hoisting drum, clutch 40 mechanism for connecting said drum to said shaft and engine reverse gear, of throttling mechanism for the engine, actuating means driven by the drum for operating said throttling mechanism at a predetermined point 45 and means connected to said clutch mechanism and said reverse gear for disengaging said actuating means.

23. In a hoisting engine, the combination with the engine shaft, a hoisting drum thereon and clutch mechanism for connecting said 50 drum to the engine shaft, of throttling mechanism for the engine, an operating shifter therefor, an actuating cam member driven from the drum for operating said shifter, a 55 reverse gear for the engine connected to disengage said actuator and shifter, clutch operating gear and means operated thereby for disengaging said actuator and shifter.

24. In a hoisting engine, the combination 60 with the engine shaft, a pair of drums on said shaft and clutch mechanisms for coupling said drums to said shaft, of throttling mechanism for the engine, separate actuating mechanisms, one driven from each of said 65 drums, for automatically operating said

throttling mechanism at predetermined points, engine reverse gear for throwing one of said actuating mechanisms out of operation and the other into operative position and means connected to each of said clutch 70 mechanisms for throwing the corresponding actuating mechanism out of operation.

25. In hoisting engines, the combination with the engine shaft, a pair of drums mounted thereon and separate clutch mechanisms for coupling said drums to said shaft, a throttling mechanism for said engine, a pair of shifters for said throttling mechanism, a pair of actuating cam members, one driven from each of said drums for operating 80 said shifters, engine reverse gear connected to shift one of said actuators and its shifter out of operative relation and the other into operative position and means connected to each of said clutch mechanisms for disengaging 85 the corresponding actuator and shifter.

26. In a hoisting engine, the combination with the engine shaft, a pair of hoisting drums thereon and separate clutch mechanisms for coupling said drums to said shaft, of 90 a throttle valve for the engine, an operating rock shaft connected to said valve, a pair of shifters on said rock shaft, a pair of actuating cam members, one driven from each of said drums for operating said shifters at predetermined points, engine reverse gear for moving 95 said shifters to throw one out of and the other into operative relation with its actuating cam member and a clutch controlling gear for each of said drums connected to 100 throw the corresponding shifter out of operative relation with its actuator.

27. In a hoisting engine, the combination with the engine shaft, a pair of hoisting drums thereon and separate clutch mechanisms for coupling said drums to said shaft, of a throttle valve for the engine, an operating rock shaft connected to said valve, a pair of shifter arms on said rock shaft, a longitudinally movable sleeve on said shaft, to 110 which sleeve said shifter arms are yieldingly connected, a pair of actuating cam members, one driven from each of said drums, for engaging and operating said shifter arm at predetermined points, engine reverse gear 115 connected to said sleeve for throwing one of said shifter arms out of and the other into operative relation with its actuating cam member and controlling gear for each of said clutch mechanisms having means for throwing 120 the corresponding shifter arm out of operative relation with its actuating cam member.

28. In a hoisting engine, the combination with the engine shaft, a pair of drums on said shaft and separate clutches for connecting said drums to said shaft, of throttle valves for the engine, an operating rock shaft connected to said valves, a pair of shifter arms keyed on said shaft and longitudu- 130

dinably movable thereon, a longitudinally shiftable sleeve on said shaft to which said shifter arms are yieldingly connected, a pair of actuating cam members, one driven from 5 each of said drums, for engaging and operating the said shifter arms at predetermined points, reverse gear for the hoisting engine, an auxiliary engine for said reverse gear, valve mechanism for the reverse engine connected to shift said sleeve to throw one of 10 said shifter arms out of operative relation and the other into operative relation with its actuating cam members, a pair of auxiliary engines for operating said clutches and valve 15 controlling mechanism for each of said clutch engines having means for moving the corresponding shifter arm out of operative relation with its actuating cam member.

29. In a hoisting engine, the combination 20 with the engine shaft and hoisting drum driven thereby, of means for throttling or cutting off the flow of motor fluid to the engine, a pair of shifters controlling the operation of said throttling means, actuating 25 mechanism driven by the engine and arranged to effect the operation of one or the other of said shifters at a predetermined point, and engine reverse gear connected to 30 said shifters and arranged to move the same to throw one into and the other out of operative relation with said actuating mechanism.

30. In a hoisting engine, the combination 35 with the engine shaft and hoisting drum driven thereby, of a throttle valve for the engine, a pair of shifter arms for controlling the operation of said throttle valve, actuating mechanism driven by the engine and arranged to effect the operation of one or the 40 other of said shifter arms at a predetermined point, and engine reverse gear connected to simultaneously move said shifter arms to throw one into and the other out of operative relation with said actuating mechanism.

31. In a hoisting engine, the combination 45 with the engine shaft and hoisting drum driven thereby, of a throttle valve for the engine, a rock shaft connected to said throttle valve, a pair of shifter arms keyed to and slidably mounted on said rock shaft, actuating mechanism driven by the engine and arranged to engage and operate one of said shifter arms at a predetermined point, and 50 engine reverse gear connected to move said arms along said rock shaft to throw one of said arms into and the other out of operative relation with said actuating mechanism.

32. In a hoisting engine, the combination 55 60 with the engine shaft and hoisting drum driven thereby, of means for throttling or cutting off the flow of motor fluid to the engine, a shifter controlling the operation of said throttling means, an actuator cam 65 geared to and rotated by the engine, and a

stationary screw for feeding said actuator cam into position to engage said shifter.

33. In a hoisting engine, the combination 70 with the engine shaft and hoisting drum driven thereby, of a throttle valve for the engine, a shifter arm connected to said throttle valve, a rotary actuator cam for operating said shifter arm, a shaft whereon said cam is mounted, a drive gear for said shaft driven by the engine, said shaft being longitudinally movable through said gear, and a stationary screw for feeding said shaft and cam longitudinally into position to engage 75 said shifter arms.

34. In a hoisting engine, the combination 80 with the engine shaft and hoisting drum driven thereby, of a throttle valve for the engine, a controlling shifter arm for said throttle valve, a rotary actuator cam for said shifter, a shaft whereon said cam is 85 fixed, a drive gear for rotating said shaft and cam driven by the engine, said shaft being hollow and longitudinally shiftable through said drive gear, and a stationary screw threaded within said hollow shaft for shifting 90 said shaft and cam longitudinally into position to engage said shifter arm.

35. In a hoisting engine, the combination 95 with the engine shaft, a pair of hoisting drums, and separate clutch mechanisms for connecting and disconnecting said drums and shaft, of means for throttling or cutting off the flow of motor fluid to the engine, a pair of shifter arms controlling the operation of said throttling means, a pair of rotary actuator cams, one geared to and rotated by each of said drums, and stationary screws for shifting said actuator cams into position to engage and operate said shifter arms at 100 predetermined points.

36. In a hoisting engine, the combination 105 with the engine shaft, a pair of hoisting drums and separate clutch mechanisms for connecting and disconnecting said drums and said shaft, of means for cutting off or 110 throttling the flow of motor fluid to the engine, a pair of shifter arms controlling the operation of said throttling means, a pair of rotary actuator cams for said shifter arms, one geared to and rotated by each of said 115 drums, stationary screws for shifting said actuator cams into position to engage and operate said shifter arms, engine reverse gear connected to said shifter arms to throw one into and the other out of operative relation with said actuator cams and means 120 controlled by the operation of each of said clutch mechanisms for throwing the corresponding shifter arm out of operative relation with its actuator cam.

SVEN T. NELSON.
